BURIAL VAULT

John D. Canedy, Oneida, N. Y., assignor to Maxwell Vault & Casket Co., Inc., Oneida, N. Y., a corporation of New York

Application September 6, 1935, Serial No. 39,482

2 Claims. (Cl. 27—17)

This invention relates to burial vaults, and more particularly, to sheet metal vaults embodying a box-like section and a cover section, together with suitable clamping devices for releasably holding the cover section in closed position across the open top of the box section.

The box and cover sections of the vault are preferably made of so called non-corrodible or slow-corroding sheet metal of uniform thickness and tenacious texture for lightness, strength and durability, to preserve and protect the enclosed casket from undue deterioration, particularly when embedded in the ground which contains more or less moisture and/or other disintegrating elements.

One of the primary objects of the present invention is to prevent the entrance of moisture from without and also to prevent the escape of gases from within the vault, so that when buried in the ground, it will resist disintegration for a longer period of time than has heretofore been practiced, and at the same time, reduce the liability of exit of any gases or vapors from the interior of the vault for sanitary reasons.

In other words, I have sought to avoid perforating any part of the body section or cover section and, at the same time, to hermetically seal the joint between said sections, and thereby to further prevent the entrance of moisture from without and escape of gases from within the vault when the cover section is closed.

In carrying out the aforementioned objects, simplicity and economy of construction have been given careful consideration but without sacrificing efficiency and effectiveness of purpose. To this end, I prefer to construct the box or body section of the vault of similar complemental sections to provide the opposite side walls and bottom, the complemental sections being preferably united at the edges of the bottom-forming portions thereof, thereby forming a medial seam in the bottom, the ends of the vault body being united with the end edges of the complemental sections aforementioned.

A further object of the invention is to provide reinforcement for the corners of the vault body, such reinforcement being preferably accomplished through the provision of corner members interlockingly engaging the contiguous walls adjacent their meeting edges, these corner members giving the effect of and substantially constituting corner posts or pilasters.

Another object of the invention is to provide the box or body section of the vault with sealing means in the nature of a laterally extending sealing flange at the upper open end of the same and

preferably as an integral part of the body section, the sealing flange being channelled or depressed for the reception of a suitable yieldable or compressible sealing gasket.

A still further object of the invention is to provide releasable clamping means for effectively clamping the cover section in sealing relation upon the open top of the vault body section, the clamping means being preferably mounted in such a manner as to avoid perforating or mutilating the vault or any part thereof.

This aim may be simply carried out by the provision of a series of clamping members arranged at intervals around the vault body, the clamping members being pivotally mounted on brackets or angle bars, which in turn are rigidly fixed, as by welding, to the walls of the vault body just below the laterally extending sealing flanges. The purpose of the pivotal arrangement of the clamping members will become more apparent as the description of the invention proceeds.

The invention also contemplates the provision of reinforcing straps extending transversely of the cover section and secured to the inner surface of the same, the ends of which straps serve to facilitate the positioning of the cover on the body section and preventing lateral movement of the cover when so positioned.

Other and further objects and advantages of the invention will be hereinafter set forth, and the novel features thereof defined by the appended claims.

In the drawings:—

Figure 1 is a side elevation of a burial vault embodying the essential features of my invention;

Figure 2 is an enlarged sectional view taken approximately on the line 2—2 of Figure 1;

Figure 3 is a fragmentary top plan view of an end portion of the vault body section, the cover having been removed to more clearly show the longitudinal medial seam in the bottom and the sealing flange construction;

Figure 4 is an enlarged fragmentary detail view showing the body and cover sections of the vault in assembled position, together with one of the clamping devices for clamping the same together, the dotted lines illustrating the released position of the clamping lever;

Figure 5 is a fragmentary detail sectional view taken approximately on the line 5—5 of Figure 8;

Figure 6 is a horizontal sectional view taken through one corner of the vault body section and particularly illustrating the interlocking corner post member for reinforcing the corner joint;

Figure 7 is a fragmentary detail elevation of a corner of the vault as shown in Figure 6, and as viewed from a diagonal position looking directly at the corner; and

5 Figure 8 is a detail sectional view taken approximately on the line 8—8 of Figure 4.

Like reference characters designate corresponding parts in the several figures of the drawings, wherein 1 denotes generally the box or body 10 section of the vault, and 2 the cover or closure member therefor which is adapted to be positioned over the upper open end of the body section, and releasably secured in such position through the clamping members 3. Of course, 15 the vault may have any desired configuration, but as is customary, it comprises an elongated substantially rectangular unit, both the body and cover being made of relatively thin sheet metal preferably of highly tenacious sheet metal of 20 uniform thickness; or if desired, it may be made of other non-corrodible or slowly corroding metal.

The body section 1 is preferably of uniform height and uniform width throughout its length and breadth, and is composed of two complementary sections, which, when joined together, 25 form the long sides 1a and 1b and bottom 5 of the body section. In other words, the complementary members are substantially in the form of angle sections which are adapted to be joined together at the edges of the bottom-forming portions thereof, as by welding, thereby providing a longitudinally extending medial seam 5c in the bottom. It is to be understood that the ends 4 of 30 the vault may be formed separately and rigidly united to the end edges of the side forming portions 1a and 1b and the bottom forming portions 5a and 5b of the bottom 5 of the complementary sections. By uniting the various parts mentioned above as by welding, a rigid unitary structure is 35 afforded and without necessitating any perforations or openings, excepting of course, the main opening at the top of the body section which affords access to the interior thereof.

As illustrated particularly in Figures 6 and 7, 40 the corners of the body section are preferably reinforced by a corner post-like reinforcing member 6, the edges of which are turned in to form interlocking flanges 7, interlockingly engaging with corresponding outwardly turned flanges 8 45 formed respectively at the meeting edges of the adjacent walls of the body section. This reinforcing member 6 may be assembled with the walls of the body section by a sliding movement of the member 6 onto the flanges 8. The corner 50 weld has been generally designated 9, the weld being normally hidden from view when the members 6 are assembled onto the vault body.

The box or body section is preferably provided with outwardly turned flanges 10, extending continuously along the upper edges of its sides and ends and around the corners thereof, these flanges being preferably an integral part of the side and end walls. The flanges are rigidly 55 united to each other at the corners of the vault body for reinforcing purposes and are provided with channels or depressions 11, opening upwardly and extending continuously along and upon the flanges and around the corners of the vault. The gasket 12 is made of any suitable 60 yieldable or compressible material, such as rubber, and is slightly greater in thickness than the vertical depth of the channels 11 so as to normally project slightly above the horizontal plane 65 of the upper edges of the side and end walls so

as to form a yielding seat for the adjacent portions of the cover section 2. As illustrated, the opposite side walls of the channels 11 are of double thickness for reinforcing purposes and for firmly holding the gasket 12 against undue lateral 5 spreading.

That is, the upper edges of the side walls 1a—1b, and end walls 4, are folded outwardly and downwardly upon themselves to form the inner walls 13 of the channels, while the upper 10 edges of the outer walls of the channels are folded outwardly and downwardly upon the outer faces of the adjacent portions thereof, as at 14. The side and end walls of the channels 11 extend 15 upwardly uniform distances from the bottoms of the channels, which latter are preferably disposed in a horizontal plane for supporting the gasket 12.

The cover section 2 is of sufficient area to cover the open top of the box or body section 1, and extends laterally across and beyond the upper 20 ends of the channels 11 and flanges 10, the outer marginal portions of the cover being disposed in substantially horizontal planes, as at 15, while the intermediate portion is preferably arched upwardly, transversely, for ornamental and reinforcing purposes, as shown clearly in Figures 1 25 and 2.

The outer edges of the cover section are provided with downwardly turned flanges 16, which project substantially to the bottom of the outer 30 walls 14 of the channel 11, primarily to conceal the sealing flanges. See Fig. 8.

One or more reinforcing straps 17 of sheet metal or equivalent material is secured, as by spot welding or otherwise, to the under side of the cover 35 section 2. These reinforcing straps extend transversely of the cover between the sides 1a and 1b of the box or body section of the vault, and have their outer ends turned downwardly or offset so as to form abutments 18. The outer faces of the 40 abutments 18 are disposed a distance apart transversely substantially equal to the distance between the inner faces of the side walls 1a and 1b, so that when the cover is placed in operative or 45 closed position upon the body section, resting upon the upper face of the gasket 12, the abutments 18 will engage the inner faces of the adjacent portions of the sides 1a and 1b, as shown best in Figures 2 and 8, to assist in holding the cover against lateral movement relatively of the body 50 section. It will also be understood that the marginal flanges 16 on the cover 2 also serve to hold the cover against lateral or endwise movement relatively to the body section when the cover is in 55 closed position.

Suitable means is provided for clamping the cover section to the upper marginal edge of the body section, and without in any way perforating or mutilating any part of either the cover or body section, or deforming the adjacent portions of either section. For this purpose, I preferably employ angle strips or bars, generally designated 19, formed of steel or other suitable metal, one flange 20 of which is positioned closely beneath the channels 11 and extends laterally outwardly 65 from the sides and ends of the body section, and the other flange 21 of which is united with the sides and ends, as by welding. I prefer to unite the angle bars 19 only with the side and end walls, and not with the channels 11. However, it will be 70 obvious that the angle bars 19 serve to reinforce the side and end walls and also reinforce the channels 11 when the clamping means presently to be described is operated to clamp the cover in closed position.

The clamping devices are generally designated as 3 and are preferably arranged in uniformly spaced relation about the vault, each clamp being pivotally mounted upon the laterally extending flanges 20 of the angle bars 19, as shown best in Figures 4 and 8.

Each of these clamping devices comprises a substantially U-shaped member 23, the upper arm 24 and lower arm 25 of which extend respectively over and under the marginal edges of the cover and sealing flanges. The lower arm of the U-shaped clamp is extended transversely of the clamp, as at 26, and is provided adjacent its free end with an upwardly projecting stud 27, which is adapted to be received in a suitable aperture provided therefor in the flanges 20 of the angle bars 19. By upsetting the upper ends of the studs 27, the clamps are pivotally secured to the angle bars, there being sufficient looseness afforded so as to permit the clamps to pivot about the vertical axis of the studs. The upper arm of the C-shaped clamp has mounted thereon a cam lever 28, as shown clearly in Figures 1 and 4, the cam portion 29 of which may be actuated by rocking the lever 25 about pivot 30, through the medium of the handle 31.

In order to position the cover member 2 to close the upper open end of the vault body, the clamping members are preferably all shifted about their vertical pivotal axes to assume positions as shown in Fig. 3, and in dotted lines in Figure 5. Thereupon, the cover is placed over the vault body and seated on the gasket 12, the flanges 16 at the marginal edges of the cover and the abutments 18 of the reinforcing straps 17 serving to facilitate the positioning of the cover and insuring that the cover will assume the correct alignment relatively to the vault body prior to clamping the cover in its closed position. Thereafter, the clamping members are shifted inwardly to the positions shown best in Figures 2, 4 and 8, it being understood that the cam levers are moved to the dotted line position of Figure 4 prior to such shifting of the clamping members. Then, by 45 rocking the cam levers 28 from the dotted line position of Figure 4 to the full line position, a firm clamping pressure will be exerted on the cover, urging the same downwardly into tight sealing engagement with the gasket 12. Owing to the abutting relation of the laterally extending flanges 20 of the angle bars 19 with respect to the sealing channels 11, the channels are reinforced and maintained absolutely rigid as the pressure is applied by the cams to the cover 2. With the 50 clamping means in clamping position, the handles 31 overlie the horizontal marginal flanges 15 of the cover and are in substantial alignment with these flanges, so that there is no likelihood of the handles becoming accidentally moved to releasing position through striking against objects during handling of the vault. In other words, the clamping means are so arranged that they do not project outwardly from the vault when in clamping position, but lie closely adjacent the surface of the cover to minimize the likelihood of accidental release thereof.

To release the cover, it is merely necessary to rock the cam levers 28, by means of the handles 31, to the dotted line position shown in Figure 4 and shift the clamping members outwardly about their vertical pivotal axes, as shown dotted in Figure 5, whereupon the cover may be readily lifted off.

When the cam levers are in clamping position, 75 the cover 2 serves to limit the downward move-

ment of the handles, but prior to reaching their downward limit, the high points of the cams 29 are firmly pressed into engagement with the upper surface of the adjacent portions of the cover section, thereby placing the gasket 12 under more or less compression, and effectively hermetically sealing the vault at the joint between the cover and the body section. The shape of the cams 29 is such that the clamping levers will remain in clamping position when the handles 31 are moved downwardly into substantially abutting relation with the cover, as shown in full lines in Figure 4.

It is to be understood that with the exception of the joint between the cover and body sections of the vault, all of the joints are preferably welded, thereby affording a substantially unitary construction. Through the use of the postlike locking members 6, the corner joints are substantially reinforced, and at the same time, these members create a distinctive ornamental effect.

It is apparent from the foregoing description that the reinforcing bars 19 and clamping devices 3 may be assembled as separate units after which the flanges 21 of the bars 19 may be spot welded or otherwise permanently secured 25 to the walls of the body section, with the laterally extending flanges 20 closely adjacent to and preferably abutting the bottom of the channels 11, thus avoiding perforating or otherwise mutilating the flanges and preserving the uniformity of the height of the vault body all around the seam so as to provide a uniform seal completely around the upper end of the vault body.

While the specific details of construction have been herein shown and described, the invention 35 is not confined thereto as alterations may be made without departing from the spirit thereof as defined by the appended claims.

Having thus described my invention, what I claim as new and desire to secure by Letters 40 Patent, is—

1. A burial vault comprising a box-like section having outturned imperforate flanges along the upper edges of its sides and ends, said flanges being provided with lengthwise channels, a cover 45 section extending across said channels when closed, reinforcing strips permanently secured to the box-like section without perforating said flanges and extending along the undersides of the flanges in contact therewith, and clamping 50 devices engaging respectively the undersides of the strips and upper surfaces of the cover section for holding the latter in its closed position without perforating the flanges and thereby to assist in making the joint between the box section and cover section liquid-tight.

2. In a burial vault, the combination with a box-like section and a cover section therefor, of means for securing the cover section to the box section including a reinforcing strip permanently secured to the box section and comprising an angle bar having one leg lying against the outer face of the box section adjacent to the upper edge of the latter, and the other leg extending outwardly therefrom, a plurality of 60 clamping members pivotally secured to the other leg of the reinforcing bar at spaced intervals with their pivotal axes vertically disposed, and cam levers pivotally mounted on the first-named members and movable into and out of engagement with the cover for holding and releasing the latter in and from its closed position.
